LOCK

George Hofmann, Boston, Mass., assignor to
American Locker Company, Inc., Boston, Mass.,
a corporation of Delaware

Application June 21, 1940, Serial No. 341,711

3 Claims. (CL. 70—395)

This invention relates to locks of the type employing a plurality of locking tumblers normally held in locking position and adapted to be forced to the released position by the insertion of a key having a corresponding number of lands of a height to perform the releasing operation. In these locks heretofore known the tumblers have ordinarily been arranged in alignment or parallel with each other which uniform arrangement facilitates unauthorized picking or tampering with the lock, as by vibrating the lock in a definite direction to move the tumblers to the released position. In accordance with my invention I provide a lock having two independent sets of tumblers in which one set is arranged relatively angular to the other set, one set extending radially of the lock and the other set extending longitudinally thereof. It will be readily apparent that such arrangement fore-stalls the above-named objection and renders my improved lock substantially pick-proof and in addition thereto provides for a greatly increased number of possible combinations. One object of my invention resides in the provision of an improved lock of this nature.

A further feature of the invention resides in the provision of a lock employing a novel key which cannot be duplicated by any key duplicating machines known or in use, whereby largely eliminating present key-duplicating troubles. The production of such an improved key for cooperating with my new lock comprises a further object of the invention.

These and other features of the invention will be best understood and appreciated from the following description of a preferred embodiment thereof selected for purposes of illustration and shown in the accompanying drawing in which

Fig. 1 is a rear end view of my improved lock nonrotatably mounted in a supporting structure,

Fig. 2 is a side elevation thereof,

Fig. 3 is a front end elevation,

Fig. 4 is a longitudinal sectional view taken on line 4—4 of Fig. 3 and showing the key in the lock,

Fig. 5 is a like view taken on line 5—5 of Fig. 3,

Figs. 6 and 7 are cross sectional views taken on lines 6—6 and 7—7 of Fig. 4,

Fig. 8 is a perspective view of the barrel portion of the key.

My improved lock embodies an outer member 10 having a bore 12 therethrough and within which is rotatably mounted an inner member 14. The outer member is the fixed unit and is mounted non-rotatably within the structure 16

5 supporting the lock, this member having a laterally extending portion 15 fitting within a corresponding recess in the structure 16 and preventing rotation of the unit about the axis of the bore 12. A plurality of plungers or tumblers 18 are mounted in bores in the portion 15 and springs 20 normally force the plungers to the locking position within the inner member 14. The outer ends of these bores are closed by a plate 22 and releasing pins 24 cooperate with the plungers, all of which is well-known construction.

10 The inner member 14 is slotted at 26 to receive the forward "Yale" key portion 28 of a key 30 having its forward edge 32 notched to provide lands for cooperating with the pins 24. A collar 34 is securely affixed to the inner member, as by sweating it thereon. In the construction illustrated, this collar is slotted along with the inner member at 26. In some cases the construction of the lock may be facilitated by slotting only the inner member at 26 and thereafter applying the collar without slotting it and in such cases the use of an independent piece at 34 is particularly desirable.

15 The member 14 is inserted into the bore 12 to a position bringing the forward face of the collar 34 into end engagement with the outer face of the member 10. The parts are held in this position by screws 36 extending through two locking plates 38 and 40 and threaded into the member 14. The plate 38 overlaps the inner end of the member 10 and is cut away at 42 to accommodate a stop pin 44 carried by the member 10. The shoulders at the ends of the recess 42 together with the pin 44 provide stops limiting the 20 rotation of the inner member 14. A washer 46 is secured by pins 48 to the inner end of the member 10 and is notched at 50 to permit passage of the key when inserting it into the lock. The rear edge of the key is notched at 52 to provide clearance for the washer when the key is rotated. This engagement of the key with the washer prevents withdrawal of the key when rotated 25 from its inserting position in which position the tumblers 18 are in alignment with the releasing pins 24.

20 The outer member 10 is bored inwardly from its front face about and parallel with the bore 12 to receive a plurality of locking plungers 54 normally forced forward by springs 56, and a plurality of corresponding bores having pins 58 therein are provided in the collar 34, the two sets of bores being respectively in alignment 30 when the lock is in the locked and key inserting

position. The springs normally force the plungers 54 to the locking position in which the plungers 54 extend into the collar 34 and the pins 58 abut against a flange 60 which serves as a stop for the pins. This flange is integral with a cap-like member 62 enclosing the collar and pinned thereto at 64.

The key 30 comprises the portion 28 for releasing the tumblers 18, a finger-gripping portion indicated at 30, and a barrel portion 66 for releasing the tumblers 54. The barrel 66 is slotted at 68 to receive the portions 28 and 30 and these parts are secured together by pins 70 or in any other suitable manner, such as welding at 71. The forward end of the barrel is adapted to fit over the inner member 14 and has recesses 72 of different depths on its forward end for receiving the pins 58. Pressure of the key against the pins 58 forces the pins rearwardly and the plungers 54 to the flush position shown in Fig. 5. A boss 74 projects outwardly from the key and the flange 60 is recessed at 76 in alignment with the slot 26 in the collar 34 for receiving this boss, and the parts are so arranged that the tumblers 18 and the tumblers 54 are forced to the flush and released position when this boss is engaged against the collar 34 as illustrated in Fig. 4.

My improved lock is applicable to various uses as will be readily apparent. The locking bolt can be applied at either end of the lock and in various positions, as indicated for example in broken lines at 77, 78, and 79. The two sets of tumblers are independent one of the other and are in different planes and relatively angular, whereby rendering the lock extremely difficult to unauthorized manipulation by vibrating or any other method or means. Furthermore, the key is a radical departure from present known keys and far more difficult to produce or duplicate. The lock also greatly increases the number of combinations possible as will be understood.

Having thus described my invention what I claim as new and desire to secure by Letters Patent of the United States is:

1. An article of manufacture, comprising a key for a lock having an outer member, an inner member rotatable therein and two sets of locking tumblers extending respectively in alignment longitudinally along and in spaced relation about the inner member, the key comprising an open

cylindrical portion engageable over the outer end of the inner member and provided with forwardly facing lands for effecting the release of the tumblers in said spaced relation and a longer portion extending forwardly beyond and disposed axially of the cylindrical portion and provided with laterally facing lands therealong for effecting the release of the longitudinally arranged tumblers.

10 2. An article of manufacture comprising a key having two parts respectively adapted to release the two sets of locking tumblers in a lock having an outer member, an inner member rotatable therein and two sets of locking tumblers respectively extending in alignment longitudinally along and in spaced relation about the inner member, one key part comprising a plug with a bore in its forward end adapting said end to engage over the outer end of the inner member and provided with lands on the forward end outside of the bore for effecting the release of the tumblers in said spaced relation, a second key part disposed axially through the plug and having a finger gripping portion rearwardly of the plug and a relatively long "Yale" key portion extending forwardly beyond the plug and provided with laterally facing lands in longitudinal alignment therealong for effecting the release of the radial tumblers, and means uniting the two parts into a unit.

30 3. An article of manufacture comprising a key for a lock having an outer member, an inner member rotatable therein and two sets of locking tumblers respectively extending in lateral alignment longitudinally along and in spaced relation about the inner member, the key comprising a cylindrical part open at its forward end and slotted diametrically through its rear portion, the forward end being engageable over the outer end of the inner member and provided with forwardly facing lands for effecting the release of the tumblers in said spaced relation, a second key part disposed in the slot and having a finger gripping portion rearwardly of the cylindrical part and a relatively long "Yale" key portion extending forwardly beyond the open end of the cylindrical part and provided with laterally facing lands in longitudinal alignment therealong for effecting the release of the radial tumblers, and means uniting the two parts into a unit.

GEORGE HOFMANN.
